DESIGN FOR A COMBINED TWIN WAFFLE IRON AND BASE

Andrew S. Knapp, St. Louis, Mo., assignor to
Knapp-Monarch Company, St. Louis, Mo., a
corporation of Missouri

Application June 9, 1937, Serial No. 69,750

Term of patent 7 years

To all whom it may concern:

Be it known that I, Andrew S. Knapp, a citizen
of the United States and a resident of the city
of St. Louis and State of Missouri, have invented
a new, original, and ornamental Design for a
Combined Twin Waffle Iron and Base, of which
the following is a specification, reference being
had to the accompanying drawing, forming part
thereof.

Figure 1 is a perspective view of a combined
twin waffle iron and base showing my new design.
Figure 2 is a top plan view thereof; and
Figure 3 is an end elevational view thereof.

I claim:

The ornamental design for a combined twin
waffle iron and base substantially as shown.

ANDREW S. KNAPP.
